UNITED STATES PATENT OFFICE.

GEORGE S. WILLITS, OF THE UNITED STATES NAVY.

PRESSURE REDUCING AND REGULATING VALVE.

SPECIFICATION forming part of Letters Patent No. 794,651, dated July 11, 1905.

Application filed April 11, 1905. Serial No. 255,033.

To all whom it may concern:

Be it known that I, GEORGE S. WILLITS, of the United States Navy, a citizen of the United States, residing in the city and county of Philadelphia and State of Pennsylvania, have invented certain new and useful Improvements in Pressure Reducing and Regulating Valves, of which improvements the following is a specification.

10 My invention relates to fluid-pressure reducing and regulating valves employed in conduits for fluid under pressure where constant pressure is desired from a supply of a higher and oftentimes variable pressure; and its 15 object is to provide a simple, compact, and reliable device whatever may be the variation of the inlet or supply pressure above that of the set delivery or outlet pressure. I attain these objects by the device illustrated 20 in the accompanying drawings, in which—

Figure 1 is a vertical longitudinal section of the entire device; Fig. 2, a detailed view of the removable seat of the lower valve-disk; Fig. 3, a vertical or cross section of Fig. 2 on line A B; and Fig. 4 is a detail view of the top end of the valve-stem, showing the groove in same for enabling the turning of the valve-stem in making the adjustment of the tension of the spring by which the 25 desired set pressure is regulated through the medium of the screw-threads on same.

Similar numerals refer to similar parts throughout the several views.

The main body 19 of the reducer and regulator is provided with inlet-passage 5 and outlet-passage 6 and with the wall or partition 7 between them and in which partition there are valved openings provided having valve-seats 8 and 9, with the space between 30 them open to the inlet-passage 5.

The regulating-valve is formed with two disks 10 and 11, with their faces or seats preferably beveled and may be made in one piece, or two, as I have shown them. The effective 35 pressure areas of the valve-disks 10 and 11 may be proportioned so that they will balance each other with reference to the fluid-pressure in any position, to enable which I employ the removable valve-seat 8 for the

purpose of affording a larger opening in the 50 partition 7 needed in such case for the passage through it of the valve-disk 11 in the assembling of the parts of the valve, inasmuch as in proportioning the valve-disks 10 and 11 the disk 11 becomes of an extreme 55 diameter, about the same as that of the disk 10, and accordingly necessitates the larger opening mentioned. This proportioning for the balance mentioned may be dispensed with and the size of the disk 11 made small 60 enough in its extreme diameter as to pass easily through the port-opening of the seat 8 and the removable seat 8 substituted by a construction of port-opening and valve-seat formed integral with the partition 7, similar 65 to that shown for the valve-seat 9, without departing from the essence of my herein-described invention.

The main body 19 is also provided with the removable bonnets 26 and 27 for convenience in construction and assembling of 70 the various parts of the device.

The regulating-valve is rigidly connected in any suitable and preferred manner to a rod or stem 12, which is in turn secured in a 75 like rigid manner to the end of a corrugated tubular spring 13, the opposite end of which is in a like rigid manner attached to the bonnet 26 of the main body 19, as is shown, for example, on the drawings herewith. For 80 convenience in construction the end of the spring 13 that is attached to the valve-stem 12 is provided with a threaded cap 15, the thread 14 on the valve-stem 12 being provided with a lock-nut 16 and a gasket 17 of 85 lead or other suitable material being placed between said nut and cap for making the connection fluid-tight under the pressure at which the device may be employed. The end of the valve-stem 12 is provided with a 90 slot or groove 30 (shown in the detail view Fig. 4) for the purpose of enabling the turning of the valve-stem 12 in its threaded connection with the cap 15 in making the necessary adjustment of the tension in the spring 13 to 95 suit the set pressure to be automatically maintained in the fluid on the delivery or outlet side of the valve. Said adjustment is ac-

complished by turning the valve-stem 12 until the screw-threads 14, in engagement with those of the cap 15, locate the latter at such position longitudinally on the stem 12 as will effect the required tension in the corrugations of the tubular spring 13, the stem 12 affording the necessary resistance through the medium of the seat 20, provided at the opposite end of same, consisting of the collar 29 on the stem 12 and hub on bonnet 27, as shown in the drawings. The tendency of the spring 13 when under the proper tension is to keep the valve-ports in partition 7 open. As shown, the device is at rest, as when fluid is not passing through it.

The corrugated tubular spring 13 is made of spring-steel or other suitable material and is proportioned as to its thickness of walls, number and size of corrugations, as also its diameter and length, all according to the conditions as to the intensity of the set pressure desired and the amount of pressure variation between the set pressure and that of the pressure of the supply of the fluid it may be desired to be employed under, as also as to the properties of the material used in the making of the spring.

A cover 18 is provided for protecting the spring 13 from dirt and injury and is attached, by means of screw-threads, to the bonnet 26, as shown on the drawings. This cover 18 is provided with one or more vent-holes 21 for permitting constant atmospheric pressure on the exterior of the corrugated tubular spring 13 and to afford a hold for a spanner-wrench in attaching and detaching same to and from the bonnet 26.

The bonnet 26 is provided with one or more port-holes 22 for the purpose of admitting freely the fluid-pressure of the outlet or delivery side of the valve to act upon the interior of the corrugated tubular spring 13, the stress of which pressure operating against the tension stress of the spring being the means by which the regulating feature of the device is effected.

The valve-disks 10 and 11 are held in alignment by the guide-bearings 23 and 24, supporting the valve-stem 12 where it passes through the bonnet 26, as also into the hub on the bonnet 27, as shown in the drawings. A small port or vent hole 25 is provided in the wall of the hub forming the guide-bearing 24 for purposes readily understood by those skilled in the art to which this invention relates.

The operation of my herein-described invention is as follows: Fluid (which, for example, may be steam) passing in at inlet-passage 5 flows through the valve-ports provided in the partition 7 until a pressure is reached on the outlet or delivery side of the valve corresponding to that at which the spring 13 has been previously set, when that

pressure acting upon the interior of the 65 spring 13 overcomes the tension stress of its corrugations and results in closing or partly closing the valve-ports in the partition 7, thus regulating the flow of the steam or fluid, and consequently the quantity of the delivery of the valve, to the demand of maintaining the predetermined pressure at which the spring 13 has been adjusted for.

It is obvious to those skilled in the art to which my herein-described invention relates that the corrugated tubular spring 13, which is of the essence of my said invention, may be employed in that class or type of pressure regulating or limiting valves commonly called "safety" or "relief" valves, 80 and therefore I do not confine the application or use of said spring to the particular form of device herein described, and shown on the herewith-accompanying drawings.

Having described my invention, what I 85 claim as new, and desire to secure by Letters Patent, is—

1. A fluid-pressure relief, or a pressure reducing and regulating valve, provided with a corrugated tubular spring; in combination 90 with a solid and rigidly-connected pressure-adjustment valve-stem, and a valve-stem joint-gasket and lock-nut; all substantially as and for the purposes shown and described.

2. In a fluid-pressure reducer and regulator, a main body 19, provided with an inlet-passage 5, an outlet-passage 6, and partition 7, separating said passages and having valved openings therethrough; in combination with a corrugated tubular spring 13 100 rigidly connected, by means of the solid valve-stem 12, to the valve forming a part of said valved openings; all substantially as and for the purposes shown and described.

3. In a fluid-pressure reducer and regulator, a main body 19, provided with an inlet-passage 5, and an outlet-passage 6, and a partition 7, separating said passages and having a valved opening therethrough provided with a removable valve-seat 8; in combination with a corrugated tubular spring 13 105 rigidly connected, by means of the solid valve-stem 12, to the valve forming a part of said valved opening; all substantially as and for the purposes shown and described. 110

4. A fluid-pressure reducer and regulator, consisting of a main body 19, provided with removable bonnets 26 and 27, and an inlet-passage 5 and an outlet-passage 6, and a partition 7, separating said passages and having valved openings therethrough one of which being provided with a removable valve-seat 8; in combination with valve-disks 10 and 11 secured, by means of a nut 28 and a collar 29, to a valve-stem 12, provided with a threaded connection to a cap 15 and secured thereto fluid-tight by means of a lock-nut 16 and gasket 17, said cap be-

ing also provided with a screw-threaded connection to the end of a corrugated tubular spring 13, the opposite end of which is attached, also by means of screw-threads, to 5 said bonnet 26, and the cover 18 for protecting said spring; all substantially as and for the purposes shown and described.

In testimony whereof I have signed my name to this specification in the presence of two subscribing witnesses.

GEO. S. WILLITS.
